DESIGN FOR A MIXING MACHINE CASING

Edith A. Jackson, Larchmont, N. Y., assignor to
American Machine & Foundry Company, a
corporation of New Jersey

Application January 19, 1935, Serial No. 54,937

Term of patent 14 years

To all whom it may concern:

Be it known that I, Edith A. Jackson, a citizen
of the United States, residing at Larchmont, in
the county of Westchester and State of New York,
have invented a new, original, and ornamental
Design for Mixing Machine Casings, of which the
following is a specification, reference being had to
the accompanying drawing, forming part thereof.

Fig. 1 is a front perspective view of the mixing
machine casing, showing my new design.

Fig. 2 is a rear perspective view thereof.

The design is embodied in casings for dough
mixers and similar articles.

I claim:

The ornamental design for a mixing machine
casing, as shown and described.

EDITH A. JACKSON.
